(57) **CLAIM**

(21) Appl. No.: **29/344,790**

The ornamental design for liquid waste transfer lower housing II, as shown and described.

(22) Filed: **Oct. 5, 2009**

DESCRIPTION

(30) **Foreign Application Priority Data**

Apr. 6, 2009 (AU) 11170/2009

FIG. 1 is a front, top, perspective view of the liquid waste transfer lower housing II of our design;

(51) **LOC (9) Cl.** 23-01

FIG. 2 is a rear, bottom, perspective view thereof;

(52) **U.S. Cl.** **D23/202**

FIG. 3 is a front elevational view thereof;

(58) **Field of Classification Search** D23/202,
D23/203, 225; 220/587, 565, 567.1; 210/532.2;
137/581

FIG. 4 is a rear elevational view thereof;
FIG. 5 is a right side elevational view thereof;
FIG. 6 is a left side elevational view thereof;

See application file for complete search history.

FIG. 7 is a top plan view thereof; and,

(56) **References Cited**

FIG. 8 is a bottom plan view thereof.
